WAXING MOP OR THE LIKE

John R. Malmo, Memphis, Tenn., assignor to Gem Incorporated, Byhalia, Miss., a corporation of Mississippi

Filed May 17, 1967, Ser. No. 7,156

Term of patent 14 years

(Cl. D37—4)

FIG. 4

FIG. 1 is a perspective view of a waxing mop, showing my new design, taken on a reduced scale.

FIG. 2 is a top perspective view thereof.

FIG. 3 is a rear elevational view thereof.

FIG. 4 is a bottom plan view thereof.

FIG. 5 is an end elevational view thereof, taken from the left of FIG. 2.

The handle is omitted in FIG. 3 and shown broken away in FIGS. 2 and 5 for convenience of illustration.

The dominant features of my design reside in the portions shown in full lines.

I claim:

The ornamental design for a waxing mop or the like, as shown and described.
